W. FOURNESS

COMPRESSOR

Filed Oct. 8, 1925

UNITED STATES PATENT OFFICE.

WILFRED FOURNESS, OF PASADENA, CALIFORNIA, ASSIGNOR, BY MESNE ASSIGNMENTS, TO THE FOURNESS DEVELOPMENT CORPORATION, OF NEW YORK, N. Y., A CORPORATION OF NEW YORK.

COMPRESSOR.

Application filed October 8, 1925. Serial No. 61,372.

My invention relates to compressors of a type particularly adapted for use in refrigerating machines, although its use is not limited, and it has among its salient objects 5 to provide an improved and compact construction and arrangement wherein the cylinder blocks are easily removable and wherein the pistons and valves are operated from eccentrics on the same shaft, the arrangement being such that different units 10 can be placed side by side within a suitable housing and operated from one shaft, both the pistons and the valves; to provide a construction in which a piston in one cylinder 15 and a valve for controlling the outlet from an adjacent cylinder move together as a unit; to provide a construction in which the entire cylinder block, pistons, and operating shaft can be removed bodily from the housing, or compression chamber in which they 20 are placed and in which the pressure is developed and retained; to provide in connection therewith an arrangement in which the pressure in said compression chamber 25 operates to cause a forced feed of lubricant to parts needing lubrication; and, in general, to provide a simple, practical, and economical compressor of the character referred to.

30 In order to fully explain my invention, I have shown one practical form or embodiment thereof on the accompanying sheet of drawings, in which,—

Figure 1 is a vertical sectional view 35 through a housing and a compressor mounted therein and in which my invention is embodied;

Figure 2 is a perspective view of one of 40 the cylinder blocks removed;

Figure 3 is a perspective view of one of 45 the piston units, showing four pistons and the arrangement whereby they are all operated from the same shaft; and

Figure 4 is a perspective view of one of 50 the eccentrics on the operating shaft, together with the block which moves the piston blocks or yokes.

Referring now in detail to the drawings, I will describe the invention as here illustrated. The housing is designated, 5, with an inlet port, 6, and with an outlet port, 7, said housing having feet portions, 8, by means of which it can be properly anchored,

and it is also provided with the cooling ribs, as 9.

Within said housing is supported a compressor body, 10, through which extends an operating shaft, 11, having bearings at 12 and 13, with suitable packing, 14, and a spring, 15, and regulating plug, 16. This 55 compressor body 10 is fastened to the removable wall 42 of housing 5. In this instance, this is effected by casting the body 10 integrally with the wall 42, which also has provisions for accommodating the inlet 60 port 6. Due to this construction, the entire 65 compressor assembly is simple. The wall 42 can be fastened to, or removed from casting 5 while the cylinder and piston assembly in body 10 is left intact on wall 42. A flexible connection, 17, is also shown.

Within the compressor body, 10, are mounted four cylinder blocks, as 18, shown detached in Fig. 2, having therein two cylinders, 19 and 20, and with ports through the sides, designated 21 and 22, and with valve openings or bores, 23 and 24, extending longitudinally of said cylinder block and parallel with said cylinders, as indicated. The cylinder blocks four of which can be 75 used, evenly spaced around a circle, are alike and each is provided with a flange, as 18', and with a packing ring, as 25, interposed between the compressor body and the flange 18'. While there are four cylinder 80 blocks in the body, 10, only the two vertical ones are shown. Screws 26 are used to secure 85 said cylinder blocks in place, substantially as indicated, supporting flanges 27, being shown in the housing. The compressor 90 body 10, forms a receiving chamber, around the cylinder blocks and the other mechanism now to be described, and into which receiving chamber the gas to be compressed is fed from the inlet port 6. The lower portion of the main housing, 5, serves 95 also as a reservoir for lubricant, designated, L, for lubricating the parts, as hereinafter referred to.

On the operating shaft, 11, within the 100 compressor body, are shown a plurality of eccentrics, 28, 29 and 30, each having an eccentric block around it, as 28', 29' and 30', one of said eccentrics and its block being 105 shown in Fig. 4, and the middle unit being shown complete in Fig. 3. Said eccentric

blocks operate yokes which carry valve members and pistons. Eccentric block 28' operates a yoke, 31, having at its opposite sides, valve members, as, 31^a, operating vertically in the valve openings, 23, 23, in the cylinder blocks, 18, 18. Eccentric block 29', operates yoke, 32, having at its opposite ends, two pistons and two valve members, as 32^a and 32^b, operating in the cylinder blocks, 18, 18, as indicated. Eccentric block 30', operates yoke 33, having at its opposite ends, pistons, 33^a, 33^b. Each of said eccentric blocks also operates a horizontal yoke and a corresponding valve member, or piston, or both. This is illustrated in Fig. 3, in which a horizontal yoke, 34, fitting across yoke 32 and eccentric block 29', is shown, carrying at its opposite ends, pistons, 34^a, and valve members 34^b. The eccentric block 28' operates a horizontal yoke, 35, shown in section, Fig. 1, while yoke, 36, also shown in section, is operated by eccentric block 30'; said horizontal yokes carrying the same, piston or valve member, or both, as are carried by the corresponding vertical yokes. The operating shaft, 11, is provided with a central lubricating port, 37, extending into it from the inner end, and the eccentrics, 28, 29 and 30, are also provided with ports therein, indicated in light broken lines and communicating with the shaft port, 37, said ports in the eccentrics being designated, 28^a, 29^a, and 30^a. The shaft bearing, 12, is provided with a port, 12^a, communicating with a vertical pipe, 38, extending down into the lubricant, L, as indicated, whereby pressure in said housing, 5, forces lubricant up through said pipe, 38, and into the lubricating ports 37, in the bearing shaft and in the eccentrics, for lubricating said eccentrics and eccentric blocks, as will be clear from the showing made. A safety valve is indicated in light broken lines, designated, 39, set in the top of the compressor body 10, and operates to relieve the pressure in the main housing, 5, should it get beyond the safety point, said safety valve operating to allow said pressure to escape back into the compressor body 10, and to the inlet port 6.

From the foregoing description and illustrations, it will be seen that I have avoided the use of poppet valves or other valves which make a noise and are affected by the pressure created within the mechanism, and have provided positive valve members working with and being similar to the moving pistons with which they move to control the outlets from the cylinders into the housing 5, within which the pressure is stored for use through the outlet port 7.

The use and operation of the device described, may be briefly set forth as follows:

The gas supply, through the inlet port, 6, is within the compressor body, 10, and around the inwardly projecting cylinder blocks. The inner ends of said cylinder

blocks are provided with the cylinder inlet ports, 21 and 22, Fig. 2, whereby as the pistons reach their extreme movement in one direction, said inlet ports, 21 and 22, are opened and the gas rushes into the cylinders, whereupon the inward movement of the pistons compresses it into the cylinder until the valve member controlling the outlet from said cylinder is moved. For example, as piston 32^a moves upwardly on the compression stroke, valve member 31^a will be moved downwardly to uncover the port, 40, and permit the escape of the compressed gas through said port 40, and valve opening 23. The valve member, 32^b, moves with piston 32^a, but controls the port, 41, from cylinder, 20, in which piston, 33^a, works. The valve members, such as 31^a, are all simple bars having uniform sectional areas throughout their lengths, since they each control but one opening, such as 40. These openings, when their corresponding valve members leave them uncovered, communicate directly with the interior of housing 5, through the valve openings, such as 23. And thus by this simple piston and valve arrangement, I have provided an efficient and practical compressor, all housed within the compressor member, 10, and enclosed within the housing, 5, within which the pressure is developed and kept, until released through outlet port 7, as will be understood by those versed in the art.

While I have shown and described one practical embodiment of the invention in this application, I am aware that changes can be made therein without departing from the spirit thereof, and I do not, therefore, limit the invention to the showing made except as I may be limited by the hereto appended claims.

I claim:

1. In a compressor, in combination, a compressor body, a plurality of cylinder blocks inserted thereinto with cylinders therein, said cylinder blocks having bores parallel with said cylinders for valve members, and having outlet ports, valve members reciprocating in said bores, and controlling only said outlet ports, pistons in said cylinders, an operating shaft, eccentrics connected for reciprocating said pistons and said valve members, and a housing for said compressor body into which discharge from said cylinders is made during the reciprocating of said pistons and said valves.

2. In a compressor of the character referred to, a plurality of cylinder blocks with cylinder and valve bores therein parallel with each other, pistons in said cylinders, valve members in said valve bores, said valve bores controlling the outlet from said cylinders, a plurality of eccentrics for operating said pistons and said valve members, some of said pistons and valve members moving

- together as a unit, means for supplying a substance to said cylinders to be compressed, and a housing into which said cylinders discharge said substance.
- 5 3. In a compressor, a plurality of cylinder and valve bores, pistons in said cylinders and valve members in said valve bores, and means for operating said pistons and valve members including an eccentric, an eccentric 10 block on said eccentric, a yoke over said eccentric block and moved in opposite directions thereby as said eccentric revolves, pistons and valve members carried by said yoke and operating in said cylinders and valve 15 bores, means for supplying gas to said cylinders, and a housing to receive said compressed gas.
4. In a compressor, a compressor body, a housing within which said compressor body 20 is mounted, said compressor body having a plurality of cylinders and valve bores therein, pistons in said cylinders and valve members in said valve bores, and means for operating said pistons and said valve members, 25 said means including a shaft, an eccentric thereon within said compressor body, an eccentric block around said eccentric, a yoke over said eccentric block and moved thereby in opposite directions, said yoke carrying 30 said pistons and said valve members, whereby to operate the same together, and means for supplying gas or the like to said compressor to be compressed into said housing.
5. In a mechanism including cylinders 35 and pistons working therein, a valve control including valve bores parallel with said cylinders, valve members to reciprocate therein, means providing outlets from said cylinders through said valve bores, whereby 40 said valve members control the outlets from said cylinders, and means for operating said pistons and valve members and including eccentrics, means for revolving the same, eccentric blocks on said eccentrics to be moved 45 thereby, yokes carried by said eccentric blocks, said yokes having said pistons and valve members connected therewith to be moved thereby, and means providing inlets and outlets from said cylinders.
6. In combination a body having a plurality of cylinder bores and a plurality of valve bores therein, each pair—a cylinder and valve bore—being parallel with each other, a piston moving in said cylinder, a valve member moving in said valve bore; an eccentric block and eccentric for operating the same, a yoke moved by eccentric block and provided at its opposite ends with a piston and a valve member, a second yoke operated by said eccentric block and provided at its opposite ends with pistons and valve members, whereby four pistons and four valve members are operated by said yokes and said eccentric block, means for supplying gas and the like to said cylinders to be compressed, and a housing to receive said compressed gas.
7. In a compressor, a housing, a detachable wall for the housing, said wall having an aperture therein, a portion at least of said aperture extending parallel to the wall and said portion opening outside of the wall, and a compressor structure supported on said wall and having an inlet opening communicating with said aperture, and an outlet port discharging into the housing, said housing having an opening forming a delivery port.
8. In a compressor, a housing, a compressor structure in said housing having an outlet port adapted to discharge into the housing, said housing being fluid tight except for an inlet and a delivery aperture, and a safety check valve in the housing and connected to the outlet port of the compressor structure for limiting the pressure in the housing.

Signed at Los Angeles, Los Angeles County, California, this 25th day of September, 1925.

WILFRED FOURNESS.
